UNITED STATES PATENT OFFICE.

HANS JENSEN, OF KANSAS CITY, MISSOURI, ASSIGNOR TO THE JENSEN-SALSBERRY LABORATORIES, INC., OF KANSAS CITY, MISSOURI, A CORPORATION OF MISSOURI.

DILATOR.

1,268,576.

Specification of Letters Patent.

Patented June 4, 1918.

Application filed November 30, 1917. Serial No. 204,581.

To all whom it may concern:

Be it known that I, HANS JENSEN, a citizen of the United States, and a resident of Kansas City, county of Jackson, and State 5 of Missouri, have invented certain new and useful Improvements in Dilators, of which the following is declared to be a full, clear, and exact description.

This invention relates to dilators of that 10 class employed for dilating the os uteri, or commonly speaking, the neck of the womb, in barren animals. The primary object of this invention is to provide a dilator which performs its function without forcibly 15 stretching the walls of the canal, whereby operations with this instrument may be performed without danger of tearing or otherwise injuring the walls of the cavity. The invention consists in the several novel features 20 hereinafter fully set forth and claimed.

The invention is clearly illustrated in the accompanying drawing, in which:

Figure 1, is a side elevation of a dilator embodying a simple form of the present invention; Fig. 2, is a cross section taken on line 2—2 of Fig. 4; Fig. 3, is a cross section taken on line 3—3 of Fig. 4; and Fig. 4, is a side elevation of the head and a fragment of the stem or handle of the instrument. 30 Figs. 2, to 4, are approximately full sized views illustrating the instrument.

Referring to said drawing, the reference numeral 5, designates the head of the instrument, to which is fixedly secured a stem or 35 handle 6, having on its free end, a knob 7. The head 5, is of conical or tapering formation throughout its greater extent, and from its thickest place it preferably tapers back to the stem 6, as at 12. The pointed end 40 of the head 5, is rounded off to afford a blunt end 8.

The face of the tapered or conical portion 9, is corrugated, the corrugations extending lengthwise of the face from the rounded 45 point to the thickest part of the head. In the preferred embodiment of the invention, the grooves 10, and ridges 11, of the corrugations

are approximately the same size, and both the grooves and ridges taper from the large end of the head to the point. The 50 grooves are continued beyond the largest diameter of the head and terminate in the face of the coned portion 12.

It is to be observed that near the point the 55 grooves and ridges are comparatively small in cross section, gradually increasing in depth, height and width as they approach the large end of the head. The exact shape of these corrugations is not material, however, to this invention broadly considered, 60 as they may vary somewhat from the precise form illustrated in the drawing. Moreover, the relative width of the ridges as compared with the width of the grooves is not material, as the ridges may be narrower 65 than the grooves, but in each case it is preferable, if not essential, that the ridges be free from sharp edges or corners to avoid cutting or tearing the walls of the cavity.

In use, the instrument is rotated while being inserted in the canal, thereby causing 70 relaxation of the muscle structures, and consequently dilation of the os. The corrugations serve the purpose of relaxing the muscle structures, thereby effecting a dilation. 75

It is to be observed that with the use of this instrument the danger resulting from excessive stretching is wholly eliminated, but that on the contrary the operation of dilating the neck of the womb may be performed 80 safely.

I claim as new, and desire to secure by Letters Patent:

A dilator comprising a conical head portion, formed with lengthwise extending corrugations on its face, the grooves of which start at the point of the cone and increase in depth from the point to the base of the cone, the ridges of the corrugations gradually merging into the grooves at the pointed end to leave no abrupt portions thereat, substantially as and for the purpose set forth. 85 90 95

HANS JENSEN.
